CONSTRUCTION FORM

Earl E. Jones, Houston, Tex.

Application January 29, 1940, Serial No. 316,102

6 Claims. (Cl. 25—131.5)

This invention relates generally to concrete forms and particularly to those of the inverted pan type used in the construction of concrete floors, ceilings and the like. It has for its general object the provision of an improved pan type form and an improved means of arranging and supporting the same.

In the past, various arrangements have been resorted to for the support of pan type forms. Chief among these are constructions in which the inverted pan type of form is made up in a plurality of relatively short lengths and these lengths are placed in overlapping relation upon wooden beams and supporting structure customarily referred to as centering.

In the conventional construction the overlapping of the sections just referred to produces a finished concrete structure which, when the forms are removed, shows seams at the points where the forms overlapped. The structure is thus somewhat unsightly in that it does not possess a smooth exterior surface where it was in contact with the forms. In addition to the fact just noted, the conventional forms require a considerable amount of carpenter work in building the wooden supports which not only support the pans along their opposite edges and extend from one end to the other of each joist formed by the pans, but in many types of pans the woodwork actually forms the bottom surface of each of the joists and is for this reason known as centering. It is, furthermore, necessary in such construction that the woodwork be removed, at considerable cost of labor and time, before the metal pans can be removed and, due to the manner in which the pans are mounted on the woodwork, this removal almost invariably results in a certain damage to the pans, shortening their useful life and tending to damage them so that they cannot be reused.

It is, therefore, an object of this invention to provide forms of the general type referred to, which may be easily and quickly removed without damage to the forms and reused many times.

It is another object of this invention to provide forms of the general type referred to, which require a minimum of temporary support.

Another object of this invention is to provide such forms in which the overlapping of the pans will be unnecessary and by which a much neater finished job may be produced.

Another object is to provide such forms which will have a very long life compared with the life of the present conventional forms.

Other objects and advantages of this invention

will become apparent from the following description taken in connection with the accompanying drawings, wherein is set forth one embodiment of this invention. In the drawings:

5 Figure 1 is a perspective view illustrating forms constructed in accordance with this invention, together with a preferred manner of mounting the same.

Figure 2 is a transverse cross section through a portion of two adjacent pans of the nature illustrated in Figure 1, showing the same after the concrete flooring has been poured therein.

10 Figure 3 is a longitudinal cross section through one of the pans illustrated in Figure 2 and through the flooring which has been poured thereon, this figure illustrating the manner in which the ends of the pan forms are mounted within the pans and on the wooden supports for the forms.

15 20 Figure 4 is a perspective view of one of the end members shown in Figure 3.

Figure 5 is a perspective view of one of the locking keys for securing together the abutting flanges of adjacent pans.

25 20 Figure 6 is a view illustrating the use of the forms shown in Figures 1 to 5 inclusive, with an additional inserted member for producing a thicker joist.

Referring now more specifically to the drawings, there is shown in Figure 1 the manner of 30 mounting forms constructed in accordance with this invention. As shown, each of the pans is of inverted channel shape, having a top 1 and sides 2 extending downwardly from the top. At the 35 lower edge of each of the sides 2, each of these pans is turned outwardly in a direction parallel with the top to form a flange 3 adapted to extend horizontally when the form is in place and to serve as a centering along the bottom of the 40 joist. Each of the flanges 3 is turned downwardly at 4 and perforated at intervals as shown in 45 5 for the purpose of receiving a locking key 6. Each of the pans illustrated rests at its opposite ends upon support members 7, these support members being notched at appropriate intervals, as shown at 8, to receive the end portions of the 50 downwardly extending flanges 4. The horizontal portions 3 of each of the pans will thus rest flatly upon the support members 7 and form an adequate bearing for supporting the pans. The flanges 4, however, will serve to stiffen the portions 3 and make it possible for each of the pans to bridge the entire space between adjacent support members 7 without any intermediate sup-

port such as the usual wooden centering or shoring.

The support members 7 will be secured either to walls 10 or to suitable supports 11, which may also serve as supports for the bridging joist soffits 12.

The ends of the pans are closed by means of end members 13 having inturned flanges 14 and 15 at the upper and end edges, respectively. The lower edges of these end members extend downwardly below the inturned end edges 15 to form a projection 16. Each of the end members 13 is of a size such that the inturned edges 14 and 15 will just fit within the end of a pan and substantially close the same. The downward extending projecting edge 16 is adapted to fit between the support member 7 and the adjacent wall or soffit. The lower extremities of the inturned end portions 15 are adapted to seat themselves upon the upper edges of the support members 7. The end members are not secured in position by any means whatever except by being clamped between the support members 7 and the adjacent soffit or other part. The support members 7 may be secured in place either by nailing or by a suitable beam tie such as illustrated at 17.

The pans may be transversely strengthened so as to carry the weight of a heavy body of concrete either by forming the pans of corrugated nature in a well known manner or by bracing them with small angle irons 18, or the like, suitably secured in place to the underside of the top portions 1 of the pans.

The inturned upper edges 14 of the end members may be perforated at 19, if desired, for the purpose of receiving suitable projections in the end of the pan and thus prevent possible slippage of the end member with respect to the pan. Each of the end members may also be provided with a special angle shaped portion 20 on its inner surface adapted to receive a wrecking bar 21, or the like, in the manner illustrated in Figure 3, for the purpose of pulling against the end member in removing the forms after the concrete has set.

The key 6 for securing together the down turned edges 4 of the pans is illustrated more in detail in Figure 5 and consists essentially of a relatively flat member capable of passing through the perforations 5 formed in the flanges 4 and having notches 21' formed in its opposite edges so that after insertion into said perforations it may be turned by means of a handle portion 22 to positively and tightly secure the down turned flanges 4 of adjacent pans to each other.

If it be desired to provide a wider joist than that for which the pans are originally made, a suitable spacer 23 may be provided, having on each of its opposite edges down turned flanges 24, corresponding to the flanges 4 and adapted to be secured to the flanges 4 in the same manner that the flanges 4 are secured to each other in the set up shown in Figs. 1 to 3, inclusive.

From the foregoing it will be appreciated that a construction has been provided in which the overlapping of pans in setting up forms has been eliminated and also in which the usual extensive shoring and supporting is rendered unnecessary. It will further be seen that the customary centering below each joist has been eliminated by the construction provided, and that the forms are such that they may be easily and quickly assembled without the use of skilled labor and without the necessity for extensive carpenter work and shoring construction.

It is further apparent that the forms provided

may be easily and quickly dismantled and removed after the concrete has set. In fact, it has been found that upon removal of the support members 7 and the end members 13, the pans 5 will in most instances drop out of their own weight. The construction is such that the removal of the pans and end members does not in any way damage them or render them unsatisfactory for further service, and thus not only is 10 the expense of placing and removing the forms substantially reduced, but the forms themselves are of much longer life than the forms of conventional construction. It is apparent by the 15 construction shown in Figure 6, joists of any desired width may be produced without eliminating from the forms any of the various advantages secured by the other parts of the construction.

Having described my invention, I claim:

1. In combination, a pair of inverted channel 20 shape pan type forms having laterally extending lower edges with depending flanges, means for securing said flanges together to form a stiffening rib, end members received by said forms to close the ends thereof, each of said end members being free from lateral projections which would prevent it from fitting entirely within said forms and having a downwardly extending part, and a single support bar extending transversely beneath said form adjacent each end thereof, said bars forming the sole support for said forms and 25 end members.

2. In combination, an open end inverted channel shape pan type form, an end member received by and closing each end of said form and keeping 35 said pan from collapsing, and a single support bar extending transversely beneath said form adjacent each end thereof, said bars forming the sole support for said form and said end members, whereby when said support is removed said end members may be removed and said form then collapsed and removed.

3. In combination, an open end inverted channel shape pan type form, an end member for closing each end of said form and keeping said 45 pan from collapsing, said end members being free from lateral projections which would prevent downward movement of said end members after concrete or the like has been poured over said form, said end members each having a downwardly projecting part projecting below the lower edges of said form, and a single support bar extending transversely of said form adjacent each end thereof, said bars having notches in their upper surfaces adapted to receive the edge portions of said forms and having a part adapted to receive and clamp said downwardly extending part of each of the end members respectively, said bars forming the sole support for said forms and end members, whereby when said support is removed said end members may be removed and said form then collapsed and removed.

4. In combination, a pair of inverted channel shape pan type forms having laterally extending lower edges with depending flanges, said flanges abutting each other, means for securing said flanges together to form a stiffening rib, end members received by said forms to close the ends thereof, each of said end members having a downwardly extending part and support means beneath said forms having openings receiving said stiffening rib, flat surfaces supporting said laterally extending lower edges of the forms, and separable parts embracing and clamping between them said downwardly extending parts on said end members.

5. In combination, a pair of inverted channel shape pan type forms having laterally extending lower edges with depending flanges, said flanges abutting each other, means for securing said flanges together to form a stiffening rib, end members received by said forms to close the ends thereof, each of said end members having a downwardly extending part and a plurality of transversely extending supporting members beneath said forms having openings therein receiving said stiffening rib and upwardly facing flat surfaces supporting said laterally extending lower edges of the forms, and separable parts embracing and clamping between them said downwardly extending parts on said end members.

6. In combination, a pair of inverted channel shape pan type forms having laterally extending

lower edges with depending flanges, said flanges abutting each other, means for securing said flanges together to form a stiffening rib, end members received by said forms to close the ends thereof, each of said end members having a downwardly extending part and support means beneath said forms having openings receiving said stiffening rib, flat surfaces supporting said laterally extending lower edges of the forms, and separable parts embracing and clamping between them said downwardly extending parts on said end members, said support means forming the sole support for said forms and end members, whereby when said support means is removed said end members may be removed and said forms then collapsed and removed.

EARL E. JONES.
